US00D355932S

United States Patent [19]Beffa*Patent Number: Des. 355,932*Date of Patent:  Feb. 28, 1995

[54] COMBINED WRITING INSTRUMENT AND CHANGEABLE INDICIA

[76] Inventor: Giorgio D. Beffa, Via Torino, No. 110, I-10040 San Gillio, Turin, Italy

[] Term: 14 Years

[21] Appl. No.: 4,771

[22] Filed: Feb. 12, 1993

[52] U.S. Cl. D19/36; D19/48; D19/51

[58] Field of Search D19/35, 36, 41-51, D19/54-58, 81-85; 401/52, 195, 88, 6, 7; 40/334, 335

[56] References Cited

U.S. PATENT DOCUMENTS

1,306,203 6/1919 Tippit 40/334

1,544,479	6/1925	Penn	40/335
2,029,877	2/1936	Knudsen	40/334
2,094,797	10/1937	Kahn	40/334
2,111,518	3/1938	Wallace	40/334
2,237,883	4/1941	Lipic	40/334

Primary Examiner—Martie Thompson
Attorney, Agent, or Firm—Levine & Mandelbaum

[57] CLAIM

The ornamental design for a combined writing instrument and changeable indicia, as shown.

DESCRIPTION

FIG. 1 is perspective view from the bottom and one side of a combined writing instrument and changeable indicia showing my new design;

FIG. 2 is a perspective view thereof from the top and opposite side; and,

FIG. 3 is a bottom right perspective view in an exploded condition.

FIG. 1

FIG 2

FIG. 3